UNITED STATES PATENT OFFICE.

WILLIAM FIDLER, OF TOPEKA, KANSAS.

STEAM PACKING DEVICE.

SPECIFICATION forming part of Letters Patent No. 276,379, dated April 24, 1883.

Application filed January 22, 1883. (No model.)

To all whom it may concern:

Be it known that I, WILLIAM FIDLER, a citizen of the United States, residing at Topeka, in the county of Shawnee and State of Kansas, have invented certain new and useful Improvements in Steam Packing Devices, of which the following is a specification, reference being had therein to the accompanying drawings.

10 My invention relates to certain new and useful improvements in rod-packing for valve-stems, piston-rods, pump-rods, &c.; and it consists in forming a stuffing-box or collar packing of metal, and in a suitable form to encircle the valve-stem or piston-rod of a steam-engine or water-engine, or a pump-rod or similar devices for pumps, and by its construction use the expanding steam to aid in forming a tight packing around the piston-rod or valve-stem, and also the same use of water in pumps when compressed by the action of the plunger.

15 The object of my invention is to construct a packing-box that can be used without coiled springs, metal rings, or fibrous material, and will allow of the use of steam or fluid in connection with its application and use.

20 Similar letters of reference refer to similar parts throughout the drawings.

25 Referring to the drawings, Figure 1 is a longitudinal sectional view of cylinder and stuffing-box joined, showing piston-head in cylinder and rod passing through stuffing-box bolted in cylinder-head. Fig. 2 is a perspective view of my device, partly in section, showing the openings for the inlet of steam or fluid.

30 In the drawings, A represents a stuffing-box or rod-packing box, formed of metal, (preferably cast,) with a right-angular projecting flange, a', extending outward from the top of the same, and having perforations near its outer edge for the reception of bolts, by which it is attached to the front head of a cylinder.

35 From the under face of flange a' extends a rim or collar, a, of suitable width and thickness, and terminating on its lower edge in a square shoulder, c', and forming with the flange a' the upper part of the outside casing of said stuffing-box. A cone-shaped extension, b, connecting at the base or inner edge of shoulder 40 c', extends downward of sufficient length, or a

distance about two-thirds the entire length of the stuffing-box. This cone-shaped extension is pierced with a series of elongated slots, g g g, the upper curved edge of said slots being near the inner edge of shoulder c'. The lower 55 edge of cone b is curved inward and formed with a tapering edge, h, leaving an aperture through which the piston-rod D will loosely pass. Cone b is formed hollow and with walls of proper thickness for durability and strength. A hollow cylinder, b', is formed with straight inner walls of sufficient diameter to permit a valve-rod or piston-rod to pass loosely inside of the same, the outer walls of said cylinder being formed of the proper size and form to fit tightly 60 inside the collar or rim a and projecting flange a'. The outer end of said cylinder terminates in a circular projecting flange, e, perforated to receive binding-screws d. Flange a' is formed on its upper surface with a circular recess of 65 the proper size to receive flange c. Screw-threaded perforations are formed at the bottom of said recess to receive the binding-screw bolts d.

70 The lower end of cylinder b' is extended to near the inner edge of cone b, terminating in a rounded outer end, i, leaving the inner walls of the same straight. A narrow annular space is provided between the end of cylinder b' and the inner face of curve h of cone b. Said cylinder b' forms the gland proper, and the space between the walls of said gland and the walls of the cone b receives steam or water from cylinder B, and by the peculiar formation and arrangement of the parts of said stuffing-box 75 the steam or water received within the space between the walls of the same is forced by expansion through the openings into the conical chamber and into the annular space between the curved edge h of cone b and the end i of 80 cylinder b', and impinges sharply against the piston-rod, thus forming a perfect and durable packing by meeting and resisting the volume of steam that otherwise might escape through the limited annular space between the gland 85 and the rod.

90 Fig. 1 shows the usual form and manner of attaching my improved stuffing-box to the front head of a steam-cylinder, B. The front head, l, is formed with a central outward ex- 95

tension, p . Said extension is formed hollow and of the same diameter its entire length, said diameter being the same as the diameter of cone b' at the inner edge of shoulder c' .

5 The outer end of extension p is turned outward to form flanges, having perforations to correspond with the perforations in flange a' , through which bolts p' pass, and by which said stuffing-box is held in place.

10 In attaching the stuffing-box to the front head, l , the small or tapered end of cone b is inserted in the outer end of extension p until the shoulder c' rests on the upper surface of said extension, when the bolts p' are inserted 15 through the perforations in the flanges, and nuts e applied to their outer ends and turned down, thus binding the parts together and holding the stuffing-box in place.

The operation is as follows: Steam is let in 20 at port n of the cylinder B , filling the cylinder above the piston-head, and, following the course marked by the curved arrows, enters the elongated slots g around cone b , filling the enlarged space between the walls of said cone 25 and the cylinder b' , whence it returns within said walls to and out of the annular space between the points i and h , formed by the cone b and the cylinder b' , impinging on the piston-rod D , and forming a strong expansive pressure that effectively prevents the passage of 30 steam through the gland or cylinder b' , and also lubricates the piston-rod.

Having thus described my invention, what I claim, and desire to secure by Letters Patent, 35 is—

1. A stuffing-box consisting of an outer and inner cylinder, the outer cylinder formed with

perforations for the admission of steam or fluid, the two cylinders forming an annular space at their free ends, through which steam 40 passing impinges against the piston-rod, substantially as and for the purpose set forth.

2. A stuffing-box having an outer hollow case formed with a flanged top, having a rim or collar extending from its under face, said rim 45 having a shoulder on its lower edge and cone-shaped perforated section extending therefrom, said section terminating in an inwardly curved edge, substantially as and for the purpose set forth.

3. A stuffing-box having an outer case and an inner cylinder, the outer case formed with a flanged top and under collar, a perforated cone-shaped extending section having its end inwardly curved, the inner cylinder formed 55 with a top projecting flange adapted to rest on the flange of the outer casing, said cylinder extending nearly to the inner face of the curved end of the outer case, substantially as and for the purpose set forth.

4. The combination of the perforated cone-shaped section b , formed as described, and having collar a and flanged top a' , the inner cylinder, b' , formed as described, with the steam-cylinder B , front head, l , rods or bolts 60 p' , and piston-rod D , substantially as shown and specified.

In testimony whereof I affix my signature in presence of two witnesses.

WILLIAM FIDLER.
